 Delaware

Application July 16, 1938, Serial No. 219,511

8 Claims. (Cl. 62—125)

This invention relates to refrigeration, and more particularly to a heat transfer system for transferring heat from a heat receiving portion at an upper elevation to a heat rejecting portion at a lower elevation.

Systems of this type include a circuit containing a heat transfer fluid that evaporates in an evaporator or heat receiving portion and takes up heat from objects in thermal transfer relation therewith, and condenses in a condenser or heat rejecting portion and gives up heat to a medium in thermal exchange relation therewith.

It is an object of the invention to provide an improvement in systems of this type for raising liquid heat transfer fluid from a heat rejecting portion at a lower elevation to a heat receiving portion at an upper elevation. Broadly, this is accomplished by circulating a working fluid in a heat transfer system by vapor lift action, and causing circulation of heat transfer fluid by circulation of the working fluid.

The working fluid preferably is of greater specific weight than the heat transfer fluid and flows in a local circuit in the system. Circulation of working fluid in the local circuit is effected by vapor lift action, and slugs of working fluid are formed as a result of such vapor lift action. The slugs of working fluid are utilized to segregate small bodies of liquid heat transfer fluid which are subsequently separated from the working fluid at the lower end of a liquid column of the working fluid. This column of working fluid reacts against the riser column of separated liquid heat transfer fluid and balances the latter.

By providing a local circuit for working fluid which is of greater specific weight than the heat transfer fluid in the system, the local circuit is capable of raising liquid heat transfer fluid through a considerable distance. The relative size of the local circuit to the heat transfer system as a whole is dependent upon the difference in specific weight of the heat transfer fluid and working fluid.

The above and other objects and advantages of the invention will be better understood from the following description and accompanying drawings forming a part of this specification, and of which:

Fig. 1 more or less diagrammatically illustrates a heat transfer system embodying the invention;

Fig. 2 is an enlarged fragmentary view of the system shown in Fig. 1 to illustrate parts thereof more clearly; and

Fig. 3 is an enlarged fragmentary view similar to Fig. 2 illustrating a modification of the invention.

In Fig. 1 the heat transfer system embodying the invention is shown in connection with a cooling element or evaporator 10 of a primary refrigeration system of a uniform pressure type, and like that described in my application Serial No. 107,852, filed October 27, 1936. The cooling element 10 constitutes a source of refrigeration and includes a casing 11 which may be embedded in insulation 12. Liquid refrigerant, such as ammonia, enters the upper part of cooling element 10 through a conduit 13. An inert gas, such as hydrogen, enters the upper part of casing 11 from the upper end of a cylinder 14 disposed therein. Liquid refrigerant evaporates and diffuses into inert gas within casing 11 to produce a refrigerating effect.

Since the refrigeration system associated with cooling element 10 does not form a part of this invention and is merely illustrative, further description thereof will not be made here. If desired, reference may be had to my aforementioned application for a description of the operation of the refrigeration system, the disclosure of which may be considered to be incorporated in this application.

The refrigerating effect produced by cooling element 10 is utilized to cool and liquefy a volatile fluid flowing through a coil 15 which is arranged about cylinder 14 and over which liquid refrigerant flows. The coil 15 constitutes the condenser or heat rejecting portion of a heat transfer system forming the subject matter of this invention.

The heat transfer system includes an evaporator or heat receiving portion 16 which is of the flooded type and at a higher elevation than condenser 15. The evaporator 16 is disposed in a thermally insulated space 17 and includes a receiver 18 having a looped coil 19 connected thereto. The evaporator 16 and condenser 15 form part of a closed fluid circuit which is partly filled with a suitable volatile liquid, such as methyl chloride, for example, that evaporates in evaporator 16 and takes up heat thereby producing cold.

Vapor formed in evaporator 16 flows through a downward extending conduit 20 which is connected at its lower end to a vertical conduit 21. The vertical conduit 21 forms part of a local circuit containing mercury or other suitable working fluid having a specific weight greater than that of the heat transfer fluid. With the introduction of vapor through conduit 20 into conduit

21, mercury is raised in a conduit 21 by vapor lift action into the upper part of a chamber 22.

Vapor and mercury are separated in chamber 22, the vapor flowing through conduit 23 into condenser 15 in which it is cooled and condensed. The upper end of condenser 15 is closed, whereby condensate will drain and flow by gravity through conduit 23 and accumulate in the lower part of chamber 22.

The slugs of mercury entering chamber 22 gravitate through accumulated condensate and enter the upper end of a vertical conduit 24. In so doing, small bodies 25 of condensate the segregated and trapped between mercury slugs 26 and moved downwardly in conduit 24. The trapped bodies 25 of condensate separate from the mercury in chamber 27 into which the lower end of conduit 24 extends. The separated condensate flows into the lower end of a riser or conduit 28 which is connected at its upper end to evaporator 16. The lower part of chamber 27 is connected to the lower end of conduit 21 to complete the circuit for the mercury or working fluid.

The path of flow of vapor from evaporator 16 includes conduit 20, upper part of conduit 21, and chamber 22. Conduit 23 and the dead end condenser 15 in effect form an extension of chamber 22, whereby the vapor is trapped above the liquid level in this chamber. The trapped vapor is condensed in condenser 15, and the path of flow of liquid returned to evaporator 16 includes chamber 22, conduit 24, chamber 27, and conduit 28. The local circuit for circulation of mercury includes conduit 21, chamber 22, conduit 24, and chamber 27.

Before starting the system for the first time the local circuit is charged with mercury, as at 29, for example. With chamber 22 and conduit 28 free of liquid heat transfer fluid the mercury will seek the lowest level in the system and solid mercury columns will be formed in conduits 21, 24, and 28. The common level of mercury in these columns must be higher than the connection of conduit 20 to conduit 21.

In starting the system evaporator 16 is charged with volatile liquid, as at 30, for example. With cooling element 10 operating to produce a refrigerating effect and volatile liquid evaporating in evaporator 16, circulation of mercury in the local circuit is instigated by vapor lift action. Since at starting there is no liquid column of heat transfer fluid in conduit 28, the segregated bodies 25 of condensate which separate from mercury in chamber 27 must escape through the mercury column in conduit 28. To insure flow of the separated condensate through this mercury column, conduit 28 should be 5 mm. or greater in internal diameter. As the column of volatile liquid builds up in conduit 28 the mercury level therein recedes and eventually falls to the lower end of conduit 24, as shown in Fig. 2. Conduits 21 and 24 have an internal diameter sufficiently small so that mercury slugs are raised by vapor lift action in conduit 21 and trapped condensate bodies 25 are lowered in conduit 24. The parts making up the mercury circuit are properly proportioned, that is, conduits 21 and 24 are of such length and conduit 20 is connected to conduit 21 at such a level that, when the mercury recedes in conduit 28 upon starting, the mercury will circulate in the manner diagrammatically shown in Fig. 2 and not completely fill the mercury circuit.

The column of mercury in conduit 24 may be referred to as the pumping head in which are

interspersed the segregated bodies 25 of volatile liquid. The weight of the liquid column in conduit 24 balances the weight of the riser column of volatile liquid in conduit 28. Liquid is raised in conduit 28 under a reaction head formed by the solid mercury column in conduit 21 which also balances the riser column of volatile liquid. With the arrangement shown a relatively small local circuit for a working fluid having a specific weight greater than the heat transfer fluid can be effectively employed to raise liquid heat transfer fluid through a considerable distance. By providing a mercury column h in conduit 21 which is 18 inches in height, for example, a methyl chloride liquid column H of 20 feet can be balanced in conduit 28 as indicated in Fig. 1.

The raising of mercury in conduit 21 is due to a pressure difference in the system resulting from condenser 15 being at a slightly lower pressure than evaporator 16. This may be best explained by assuming that the pressure in conduit 20 is at a certain value. At a point in conduit 24 somewhat above the connection of conduit 20 to conduit 21, the pressure is the same as in conduit 20. From this point in conduit 24 the pressure decreases upwardly through the liquid, so that the pressure in chamber 22 above the liquid column is less than the pressure in conduit 20. Consequently, there is a pressure difference between chamber 22 and conduit 20, whereby liquid is caused to rise due to vapor lift action. This pressure difference is relatively small.

Due to the relatively large volumes of vapor entering through conduit 20, the mercury column in the upper part of conduit 21 is lightened and raised against a small reaction head formed by the liquid column in conduit 24 and chamber 22. This small reaction head is a part of the weight of liquid in conduit 24 and chamber 22 which balances the weight of the mercury slugs and vapor in conduit 21 above the connection of conduit 20.

By circulating mercury in the local circuit by vapor lift action, successive bodies 25 of condensate are segregated at the upper end of conduit 24 and transferred from chamber 22 to chamber 27 which is at a constantly greater pressure. The pressure in chamber 27 corresponds to the height of mercury column h in conduit 21, whereby condensate is effectively returned to evaporator 16 through a considerably greater distance H in conduit 28.

To prevent evaporation of volatile liquid in the local circuit, chamber 22, conduit 24, chamber 27, and conduit 21 may be embedded in insulation 12 along with cooling element 10. Likewise, vertical conduit 28 may be embedded in insulation 31 to prevent evaporation of volatile liquid in this conduit.

In the embodiment in Figs. 1 and 2 mercury is raised in conduit 21 against a reaction head formed by liquid in conduit 24 and chamber 22. This reaction head is dependent upon the level of mercury in conduit 21 at the connection of vapor conduit 20. With changes in height of volatile liquid in conduit 28, the mercury level in conduit 21 will also vary since this mercury column balances the volatile liquid column. The reaction head for raising mercury in conduit 21 will therefore vary with changes in mercury level in this conduit.

In Fig. 3 is illustrated a modification of the invention whereby variations in reaction head for raising mercury is minimized. Fig. 3 is a diagrammatic view similar to Fig. 2 in which

conduit 20a corresponds to conduit 20, chamber 22a corresponds to chamber 22, and conduits 23a and 28a correspond to conduits 23 and 28.

Vapor formed in the evaporator at the upper elevation flows through conduit 20a into conduit 32 which forms part of the local circuit for circulation of mercury. By introducing vapor into conduit 32, mercury is raised in this conduit by vapor lift action into chamber 22a. Vapor is cooled and condensed in the dead end condenser connected to conduit 23a and drains back into chamber 22a. Bodies 25a of condensate are segregated by mercury slugs 26a at the upper end of conduit 24a, and the segregated bodies 25a of condensate move downwardly in this conduit. At the lower end of conduit 24a segregated bodies 25a of condensate are relieved and move upwardly in chamber 21a. The upper part of chamber 21a is connected to conduit 28a through which liquid is raised to the evaporator at the upper elevation.

The lower part of chamber 21a is connected to a vertical conduit 21a which in turn is connected at its upper end to a chamber 33. The lower part of chamber 33 is connected to the lower end of conduit 32 to complete the local circuit for circulation of mercury. The upper part of chamber 33 is connected by a conduit 34 to the vapor space in chamber 22a. Chamber 33 may be provided with a charging valve 35 through which the local circuit can be charged with mercury.

Circulation of mercury and heat transfer fluid in the modification in Fig. 3 is effected in the same manner as in the embodiment in Figs. 1 and 2 and described above. In Fig. 3 the riser column of volatile liquid in conduit 28a and chamber 21a is indicated by H' and corresponds to the height H in Fig. 1. This column of volatile liquid is balanced by an effective mercury column h' in the local circuit for mercury.

With variations in the height of the volatile liquid column, variations will occur in the height of the mercury column in conduit 21a and chamber 33. The rise and fall of mercury in chamber 33 will be very small since the cross-sectional area of the chamber is relatively large and considerably greater than that of chamber 21a. Chamber 33 therefore serves as a liquid leveling chamber whereby the liquid level therein will only vary very slightly during operation of the system.

The difference in height of mercury in chamber 33 and in conduit 32 represents the reaction head RH by which mercury is raised in conduit 32, as indicated in Fig. 3. The weight of the mercury column represented by the reaction head balances the weight of the mercury slugs and vapor raised in conduit 32. Due to the small pressure difference in conduit 20a and chamber 33 resulting from condenser 15 being at a slightly lower pressure than the evaporator, vapor entering conduit 32 through conduit 20a is effective to raise mercury by vapor lift action.

The modification in Fig. 3 is started in a manner similar to that described above in connection with Fig. 2. Thus, the mercury circuit may be charged with mercury so that mercury level will be in the lower part of chamber 33. Upon starting the mercury level recedes in vertically extending chamber 21a, in the same manner that it recedes in conduit 28 in Fig. 2, until it eventually falls to the level shown in Fig. 3. The chamber 33 is sufficiently large to take care of the mercury receding in vertically extending

chamber 21a, whereby the mercury will circulate in the manner diagrammatically shown in Fig. 3 during operation of the heat transfer system.

While several embodiments of the invention have been shown and described, such variations and modifications are contemplated as fall within the true spirit and scope of the invention, as pointed out in the following claims.

10. What is claimed is:
  1. In a heat transfer system including a first circuit partly filled with a volatile liquid and having an evaporation portion at an upper elevation and a condensation portion at a lower elevation, a second circuit containing a liquid of greater specific weight than the volatile liquid, and means associating said circuits whereby liquid in said second circuit is circulated by vapor formed in said first circuit and circulation of liquid in said second circuit effects lifting of liquid in said first circuit between said elevations.
  15. In a heat transfer system including a first circuit partly filled with a volatile liquid and having an evaporation portion and a condensation portion, a second circuit containing a liquid of greater specific weight than the volatile liquid and immiscible therewith, means to circulate the liquid of greater specific weight in said second circuit, and means to cause flow of volatile liquid from said condensation portion to said evaporation portion in said first circuit by circulation of the liquid of greater specific weight in said first circuit.
  20. A method of circulating a volatile fluid which includes condensing vaporized fluid and accumulating the condensate, segregating the condensate by slugs of a working fluid having a greater specific weight than the condensate, so as to produce a liquid column of the slugs and trapped segregated bodies of condensate extending downwardly from the accumulated condensate, separating the trapped condensate from working fluid in the lower part of said column, raising the condensate against a reaction head formed by another liquid column of working fluid, and lifting working fluid in said other column by vapor of said volatile fluid and introducing such fluid as liquid slugs into the accumulated condensate.
  25. In the art of transferring heat with the aid of a system partly filled with a volatile liquid and in which liquid is evaporated at an upper elevation and vapor is condensed at a lower elevation, the improvement which includes raising a first fluid by vapor-lift action above a liquid level of a body of a second fluid of less specific weight, separating the vapor from the first fluid, condensing the separated vapor above the liquid level of the second fluid and allowing the condensate to fall by gravity to form the body of second fluid, producing a liquid column of the first and second fluids in which bodies of the second fluid are segregated in the first fluid, separating the segregated bodies of the second fluid from the first fluid in the lower part of the liquid column, and collecting the segregated bodies to form a riser column of the second fluid in which liquid is raised under a reaction head formed by a liquid column of the first fluid.
  30. A method of circulating volatile fluid which includes accumulating condensate of said fluid in a place of accumulation, segregating the condensate by slugs of a working liquid of greater specific weight than the condensate and immiscible therewith to produce a column of slugs of the working liquid and trapped segregated bodies
  35. A method of circulating volatile fluid which includes condensing vaporized fluid and accumulating the condensate, segregating the condensate by slugs of a working fluid having a greater specific weight than the condensate, so as to produce a liquid column of the slugs and trapped segregated bodies of condensate extending downwardly from the accumulated condensate, separating the trapped condensate from working fluid in the lower part of said column, raising the condensate against a reaction head formed by another liquid column of working fluid, and lifting working fluid in said other column by vapor of said volatile fluid and introducing such fluid as liquid slugs into the accumulated condensate.
  40. In the art of transferring heat with the aid of a system partly filled with a volatile liquid and in which liquid is evaporated at an upper elevation and vapor is condensed at a lower elevation, the improvement which includes raising a first fluid by vapor-lift action above a liquid level of a body of a second fluid of less specific weight, separating the vapor from the first fluid, condensing the separated vapor above the liquid level of the second fluid and allowing the condensate to fall by gravity to form the body of second fluid, producing a liquid column of the first and second fluids in which bodies of the second fluid are segregated in the first fluid, separating the segregated bodies of the second fluid from the first fluid in the lower part of the liquid column, and collecting the segregated bodies to form a riser column of the second fluid in which liquid is raised under a reaction head formed by a liquid column of the first fluid.
  45. A method of circulating volatile fluid which includes accumulating condensate of said fluid in a place of accumulation, segregating the condensate by slugs of a working fluid having a greater specific weight than the condensate, so as to produce a liquid column of the slugs and trapped segregated bodies of condensate extending downwardly from the accumulated condensate, separating the trapped condensate from working fluid in the lower part of said column, raising the condensate against a reaction head formed by another liquid column of working fluid, and lifting working fluid in said other column by vapor of said volatile fluid and introducing such fluid as liquid slugs into the accumulated condensate.
  50. In the art of transferring heat with the aid of a system partly filled with a volatile liquid and in which liquid is evaporated at an upper elevation and vapor is condensed at a lower elevation, the improvement which includes raising a first fluid by vapor-lift action above a liquid level of a body of a second fluid of less specific weight, separating the vapor from the first fluid, condensing the separated vapor above the liquid level of the second fluid and allowing the condensate to fall by gravity to form the body of second fluid, producing a liquid column of the first and second fluids in which bodies of the second fluid are segregated in the first fluid, separating the segregated bodies of the second fluid from the first fluid in the lower part of the liquid column, and collecting the segregated bodies to form a riser column of the second fluid in which liquid is raised under a reaction head formed by a liquid column of the first fluid.
  55. A method of circulating volatile fluid which includes accumulating condensate of said fluid in a place of accumulation, segregating the condensate by slugs of a working fluid having a greater specific weight than the condensate, so as to produce a liquid column of the slugs and trapped segregated bodies of condensate extending downwardly from the accumulated condensate, separating the trapped condensate from working fluid in the lower part of said column, raising the condensate against a reaction head formed by another liquid column of working fluid, and lifting working fluid in said other column by vapor of said volatile fluid and introducing such fluid as liquid slugs into the accumulated condensate.
  60. A method of circulating volatile fluid which includes accumulating condensate of said fluid in a place of accumulation, segregating the condensate by slugs of a working fluid having a greater specific weight than the condensate, so as to produce a liquid column of the slugs and trapped segregated bodies of condensate extending downwardly from the accumulated condensate, separating the trapped condensate from working fluid in the lower part of said column, raising the condensate against a reaction head formed by another liquid column of working fluid, and lifting working fluid in said other column by vapor of said volatile fluid and introducing such fluid as liquid slugs into the accumulated condensate.
  65. A method of circulating volatile fluid which includes accumulating condensate of said fluid in a place of accumulation, segregating the condensate by slugs of a working fluid having a greater specific weight than the condensate, so as to produce a liquid column of the slugs and trapped segregated bodies of condensate extending downwardly from the accumulated condensate, separating the trapped condensate from working fluid in the lower part of said column, raising the condensate against a reaction head formed by another liquid column of working fluid, and lifting working fluid in said other column by vapor of said volatile fluid and introducing such fluid as liquid slugs into the accumulated condensate.
  70. A method of circulating volatile fluid which includes accumulating condensate of said fluid in a place of accumulation, segregating the condensate by slugs of a working fluid having a greater specific weight than the condensate, so as to produce a liquid column of the slugs and trapped segregated bodies of condensate extending downwardly from the accumulated condensate, separating the trapped condensate from working fluid in the lower part of said column, raising the condensate against a reaction head formed by another liquid column of working fluid, and lifting working fluid in said other column by vapor of said volatile fluid and introducing such fluid as liquid slugs into the accumulated condensate.
  75. A method of circulating volatile fluid which includes accumulating condensate of said fluid in a place of accumulation, segregating the condensate by slugs of a working fluid having a greater specific weight than the condensate, so as to produce a liquid column of the slugs and trapped segregated bodies of condensate extending downwardly from the accumulated condensate, separating the trapped condensate from working fluid in the lower part of said column, raising the condensate against a reaction head formed by another liquid column of working fluid, and lifting working fluid in said other column by vapor of said volatile fluid and introducing such fluid as liquid slugs into the accumulated condensate.

of condensate extending downward from the accumulated condensate, separating the trapped bodies of condensate from the working liquid in the lower part of said column, forming a column of the separated condensate, forming a column of the separated working liquid, continuing transfer of the trapped bodies of condensate to the column of condensate to cause upward flow of liquid in this column, taking liquid from the upper end of said condensate column and evaporating the liquid to form vapor, utilizing said vapor to lift liquid in said column of working liquid by vapor lift action to form the slugs of working liquid and cause flow thereof to the place of condensate accumulation.

6. In the art of transferring heat with the aid of a system partly filled with a liquid heat transfer fluid, the improvement which includes forming a liquid column of working fluid of greater specific weight than the heat transfer fluid, repeatedly segregating bodies of liquid heat transfer fluid by liquid slugs of working fluid at a given level above the lower end of said liquid column and lowering such segregated bodies of heat transfer fluid and slugs of working fluid to the lower end of the liquid column, separating the segregated bodies of heat transfer fluid from

working fluid at the lower end of said liquid column, forming a second liquid column of the separated bodies of heat transfer fluid which balances said first column, continuing to introduce 5 heat transfer fluid from said first column into said second column to cause upward flow of liquid in the latter, evaporating heat transfer fluid taken from the upper end of said second column to form vapor, and utilizing the vapor to raise working fluid from the lower end of said first column upward by vapor lift action to said given level.

10 7. In a heat transfer system, a circuit containing a volatile fluid and having an evaporation portion at an upper elevation and a condensation portion at a lower elevation, and means for raising condensate between said elevations utilizing another fluid circulated by vapor from said evaporation portion.

15 8. A method which includes circulating a first fluid by vapor-lift action, flowing a second fluid in a path of flow having a portion where heat is absorbed by vaporization of said second fluid, causing circulation of the second fluid by circulation of the first fluid, and utilizing vapor formed in said heat absorption portion to effect said vapor-lift action.

ALBERT R. THOMAS.
